UNITED STATES PATENT OFFICE.

EDWARD F. BEACH, OF PITTSBURGH, PENNSYLVANIA, ASSIGNOR TO H. H. ROBERTSON COMPANY, OF PITTSBURGH, PENNSYLVANIA, A CORPORATION OF PENNSYLVANIA.

VENTILATOR.

Application filed January 16, 1923. Serial No. 612,976.

This invention relates to a ventilator and more particularly to a ventilator base. The invention has for its object to provide a ventilator base with which labor and expense of 5 erecting and installing ventilators on roofs of buildings and like structures of different pitch may be simplified and reduced to a minimum.

To this end, the ventilator base is composed of a hollow upper member to which the 10 ventilator is connected, and a lower member having an upright portion with which the hollow upper member communicates, and is preferably secured thereto in a substantially 15 vertical position.

The lower member is designed to be applied to the roof, either flat or pitched, and the upright portion of said lower member is suitably constructed so as to enable the 20 hollow upper member of the base to be made as a standard for all roofs and to be preferably secured to the said upright portion in a substantially vertical position irrespective of the character of the roof.

25 These and other features of the invention will be hereinafter described and pointed out in the claim at the end of this specification.

In the drawings illustrating the preferred 30 form of the invention, Fig. 1 is an elevation with parts in section illustrating a ventilator erected upon the ridge of a roof by means of a base embodying the present invention;

Figs. 2 and 3 are elevations showing the 35 ventilator base applied to a pitch and a flat roof respectively;

Fig. 4, an inverted plan of the ventilator base in the position shown in Fig. 3; and

Fig. 5, a cross section on the line 5—5 of 40 Fig. 1.

Referring to the drawing, the ventilator base illustrated therein comprises in general a hollow upper member 10 having provision for connection to the ventilator 12, preferably by an upstanding pipe section 13 arranged to fit into the lower end of the ventilator. The hollow upper member 10 has cooperating with it a lower member 14 for connecting it and the ventilator with the 50 opening in the roof.

For erecting ventilators upon the ridge of the roof, the ventilator base will preferably be constructed as illustrated in Fig. 1, wherein the lower member 14 is shown as formed 55 in two parts or halves, each having an up-

right portion 15 extended into the lower end of the hollow upper member 10 and cooperating therewith to form an extension thereof. Each upright portion 15 is provided with a curved outer end wall 17, with 60 opposed side walls 18 preferably of approximately sector shape and provided with relatively short inner edges 22, which are inclined upwardly toward said curved outer 65 walls 17, and with a flange 19 extended around and secured to the lower ends of the walls 17, 18. The upright portions 15 are arranged to be angularly adjustable toward and from each other to enable them to rest upon the ridge and conform to roofs of different 70 pitch. The curvature of the end walls 17 is preferably such as to permit the angular movement of the upright portions 15 and retain the end walls 17 in engagement with the internal surfaces of the end walls of the 75 hollow upper member 10, to permit the upright portions to be bolted or otherwise secured to the upper member 10. In practice the adjacent portions of the flange 19 upon 80 each of the upright portions 15 are preferably connected together and are capable of being bent during the erection of the ventilator base, to secure the desired angular adjustment of the parts.

The side walls 18 of the two parts or 85 halves of the lower member 14 may be made of one piece of sheet metal, and are cut away as shown to form V-shaped openings 20 to assist in the angular adjustment of the upright portions 15 and whose walls form the 90 inclined edges of said upright portions.

When the ventilator is to be erected upon a pitch roof at a place other than at the ridge, one part or half of the lower member 14 used on the ridge will be employed to 95 form the lower member of the base for the pitch roof, as illustrated in Fig. 2, it having opposing segmental shaped side walls 18, curved outer end walls 17 and upwardly and rearwardly inclined inner edges 22. The 100 lower member 14 in such cases is also provided with a flange 19 secured to the lower ends of the side and end walls as shown. The end walls 17, 22 are extended in the same general direction to permit the flange 105 19 to assume different angular positions, according to the pitch of the roof, so as to enable the upper member 10 to be fitted to the lower member and yet be in a substantially vertical position.

Both of the constructions illustrated in Figs. 1 and 2 may be used upon a flat roof such as is illustrated in Fig. 3. In such instance the flange of the lower member 14 assumes a horizontal position and the upper member 10 a vertical position, with the upright portion of the lower member extended up into the upper member. When the lower member 14 is composed of two parts or halves as shown in Fig. 1, the V-shaped notch or opening 20 will be extended to near the flange 19 to facilitate angular adjustment of the two parts to the roof on opposite sides of the ridge, and also to enable the said parts to be easily severed for use individually as shown in Fig. 2.

From the above description, it will be observed that the improved ventilator base enables ventilators to be easily and economically erected upon roofs of different pitch and also upon different parts of the roof. In practice, the hollow upper member may be manufactured as a standard, and the lower member made of different sizes and shapes, and both may be stored in warehouses, so that when a job arises, a standard upper member may be shipped to the job with a plurality of different shaped lower members, one of which is selected on the job to be applied to the ridge of the roof, the inclined side, or to a flat roof, as the case may be.

The present invention, therefore, eliminates the necessity for accurate data as to the exact pitch of the roof, and at the same time eliminates sheet metal work at the job for fitting the ventilator to roofs of different pitch. In addition, all of the manufacturing operations in connection with the ventilator and ventilator base may be performed in the shop or factory and thus reduce the total cost of the erected ventilator.

While the preferred embodiment of the invention has been illustrated and described, it will be understood that the invention may be embodied in other forms within the scope 45 of the following claim.

Claim:

A ventilator base comprising a hollow upper member having provision for connection with a ventilator, and a lower member composed of two parts or halves, each having curved outer end walls and upright side walls separated at their inner ends by a substantially V-shaped notch and connected together at their bottom portions by outwardly 50 extended side flanges capable of being bent to move the two halves into different positions with relation to each other.

In testimony whereof, I have signed my name to this specification.

EDWARD F. BEACH.
